J. M. MARONEY

DIRECTION INDICATING SIGNAL

Filed May 14, 1928

Patented Sept. 25, 1928.

1,685,339

UNITED STATES PATENT OFFICE.

JOHN MILTON MARONEY, OF OAKLAND, CALIFORNIA.

DIRECTION-INDICATING SIGNAL.

Application filed May 14, 1928. Serial No. 277,647.

My invention relates to improvements in direction indicating signals, and it consists in the combinations, constructions and arrangements hereinafter described and claimed.

An object of my invention is to provide a direction indicating signal which primarily consists of a casing having an opening and a tubular expansible and contractible member projected out of the casing when air is applied thereto and drawn back into the casing when air is withdrawn therefrom. The invention contemplates putting at least two of the signals upon the car, these preferably being disposed at the rear. A valve positioned near the driver controls the flow of air into and out of the signals.

A further object of my invention is to provide a device of the type described which is extremely simple in construction and in which the tubular member is reinforced by spaced rings.

Other objects and advantages will appear in the following specification, and the novel features of the device will be particularly pointed out in the appended claims.

My invention is illustrated in the accompanying drawing forming a part of this application, in which

30 Figure 1 is a schematic showing of the two signals operatively connected to the actuating mechanism;

Figure 2 is an enlarged sectional view of the signal;

35 Figures 3 and 4 are views of a novel valve used in conjunction with the signal; and

Figure 5 shows the collapsible tubular member used in a toy pipe.

In carrying out my invention, I provide a casing 1 having an open end 2 and a closed end 3; and a pipe 4 communicating with the interior of the casing. In the casing I dispose a collapsible tubular member indicated generally at 5. The wall of this member may be made of rubber or other suitable flexible material. It may be transparent in case a light is disposed on the inside for illumination, or it may be opaque and the outer surface thereof colored for flashing a signal when the member is elongated.

The tube 6 is secured to a disc 7 disposed on the inside of the casing and connected thereto, and to a disc 8 that moves out from the casing into the dotted line position shown in Figure 2 when the tube is extended. Reinforcing rings 9 are disposed along the

inside of the tube at spaced intervals, and these rings prevent the collapsing of the tube in any direction except that along its longitudinal axis. It will be seen that when air is drawn from the tube, the tube will be collapsed and be moved into the full line position shown in Figure 2.

I have shown in Figure 1 two signals indicated by A and B. Both are identical and are constructed as already set forth. The signal A indicates a left turn, while B indicates a right turn. Air conduits 4 and 10 lead from the signals to a valve casing indicated at 11 (see Figure 4). A valve 12 is mounted within the casing and has passageways 13 and 14 therein of the shape shown. The valve casing is preferably disposed near the steering wheel of the automobile where the handle 15 of the valve may be readily manipulated. A pipe 16 leads from the valve casing 11 to the intake manifold 17 of the automobile engine 18. A pipe 19 leads from the casing to a storage tank 20. Air is pumped into this tank by a pump 21 and this air is kept at a predetermined pressure.

From the foregoing description of the various parts of the device, the operation thereof may be readily understood.

When the handle 15 is in neutral position, i. e. when the handle lies above the pipe 16 as it emerges from the casing 11, the passageway 14 places the pipes 4 and 10 in communication with the suction pipe 16. The engine 18, when running continually, sucks air through the pipe 16 and therefore places a partial vacuum upon the signals A and B and keeps the extensible members 5 contracted.

If the driver intends to turn to the left, he merely swings the handle 15 into the full line position shown in Figures 1 and 3. This places the pipe 4 in communication with the pipe 19, while the pipe 10 is still in communication with the pipe 16. Air will flow from the reservoir 20 through the pipes 19 and 4 and into the signal A extending the member 5 as shown. The signal will be rigidly held in extended position as long as the operator so desires.

When the driver wishes to return the signal, he merely swings the handle 15 back into neutral position, and this cuts off the pipe 4 from the pipe 19 and again places it in communication with the pipe 16. The right hand signal B can be actuated in the same manner, the handle 15 in this instance being swung to the right, which places the pipes 10

and 19 in communication and the pipes 4 and 16 in communication.

In Figure 5 I show a casing 25 shaped into the bowl of a pipe. A pipe stem 26 communicates with the bowl and has a passageway 27 that leads to the interior of a collapsible member 28 which is similar to the member 5. A blowing upon the pipe stem 26 will elongate the member 28, and a drawing of the air 10 back through the pipe will collapse the member. The member 28 may be colored bright so as to attract attention, and may be made of a material to withstand severe use.

Although I have shown and described two 15 embodiments of my invention, it is to be understood that the same is susceptible of various changes, and I reserve the right to employ such changes as may come within the scope of the appended claims.

20 I claim:

1. A casing having a closed end and an open end, a collapsible member normally disposed within said casing and having one end thereof secured to the casing, means for admitting air to said member and for with- 25

drawing air from said member, and reinforcing rings disposed at intervals along said member.

2. An automobile signal comprising a pair 30 of casings, collapsible and extensible members mounted in said casings, an air reservoir, means for pumping air into said reservoir, a valve for placing said members in communication with said reservoir, a pipe leading from said valve to the intake manifold 35 of the engine, said valve being adapted to place said pipe in communication with said members for retracting them, each member being reinforced by spaced-apart rings.

3. A casing having an open end and a 40 closed end, a flexible member circular in cross section normally disposed in said casing, means for admitting air into said member and for exhausting air therefrom, spaced-apart rings disposed in said member, the portions of said member disposed between said 45 rings being foldable for permitting said member to be withdrawn into said casing.

JOHN MILTON MARONEY.
